US0D1047781S

(12) **United States Design Patent** (10) Patent No.: **US D1,047,781 S**
(45) Date of Patent: ** Oct. 22, 2024

(54) **INVALID CARRIAGE**

(71) Applicant: **AbilityRide LLC**, Jacksonville, FL (US)

(72) Inventors: **Susan Gopaul**, Jacksonville, FL (US); **Adelle Starin**, Little Falls, MN (US); **Aaron Cadotte**, Hoffman Estates, IL (US)

(**) Term: **15 Years**

(21) Appl. No.: **35/519,628**

(22) Filed: **Nov. 20, 2023**

(80) **Hague Agreement Data**

Int. Filing Date: **Nov. 20, 2023**

Int. Reg. No.: **DM/234143**

Int. Reg. Date: **Nov. 20, 2023**

Int. Reg. Pub. Date: **Jan. 5, 2024**

(51) **LOC (14) Cl.** **12-12**

(52) **U.S. Cl.**

USPC **D12/129**

(58) **Field of Classification Search**

USPC D12/129

CPC B62B 7/00-04; B62B 9/00-28

See application file for complete search history.
